APPARATUS FOR MAKING ROOF TRUSSES
 Grayson Hunter Bowers, Jr., 231 E. Patrick St.,
 Frederick, Md. 21701
 Filed Sept. 16, 1966, Ser. No. 580,057
 U.S. Cl. 269—156 3 Claims
 Int. Cl. B25b 1/02

The present invention relates to apparatus for assembling structural elements to form prefabricated building units and the invention more specifically pertains to equipment for supporting preformed rafters and other preshaped structural elements in proper relationship to each other to provide prefabricated roof trusses.

An object of the invention is to provide apparatus for supporting rafters in inclined positions with respect to each other and in sloping relation to the horizontal including means for maintaining angular ends of the rafters in abutting relationship and means supporting and holding a bottom chord of the truss in proper relationship with the rafters while such structural elements are secured to each other.

Other objects and features of the invention will be appreciated and become apparent to those skilled in the art to which the invention pertains as the present disclosure proceeds and upon consideration of the annexed drawings taken in conjunction with the following detailed description wherein an exemplary embodiment of the invention is disclosed.

In the drawings:

FIG. 1 is a front elevational view of apparatus embodying the invention.

FIG. 2 is a sectional view on a larger scale and taken on the line 2—2 of FIG. 1.

FIG. 3 is a similar view taken on the line 3—3 of FIG. 1.

FIG. 4 is a side elevational view of one of the stirrups for supporting the bottom chord of a truss and taken on the line 4—4 of FIG. 1.

FIG. 5 is a side elevational view of an abutment member for engaging an end of the top chord of a truss and taken on the line 5—5 of FIG. 1.

FIG. 6 is a side elevational view of a stop member for the bottom chord of a truss and taken on the line 6—6 of FIG. 1.

FIG. 7 is an elevational view taken on the line 7—7 of FIG. 1 showing means for urging the bottom chord of a truss into engagement with the web means of a truss.

FIG. 8 is a fragmentary elevational view of end portions of a roof truss illustrating means for maintaining the rafters and the bottom chord in assembled relationship.

FIG. 9 is a fragmentary elevational view showing the manner in which the bottom chord of a truss is maintained in engagement with a king post or web means of the roof truss.

FIG. 10 is a perspective view of an assembled roof truss.

The invention pertains to apparatus for holding pre-shaped structural elements in proper assembled relationship while such elements are secured to each other to provide a roof truss and an example of such a prefabricated building unit is shown in FIG. 10. It comprises rafters 12 and 14 with their pre-cut ends in abutting relationship to form a top chord of the truss. The rafters may have any suitable angular relationship to provide a desired pitch for the roof of a building and the abutting end surfaces of the rafters 12 and 14 may be formed so that they are in full engagement for the desired slope of the roof. The truss includes a bottom chord 16 which may be of one piece and forms a ceiling joist. Any type of web arrangement may be provided for joining the

2

bottom and top chords and in one embodiment such web means takes the form of a king post 17. The surfaces at the ends of the bottom chord 16 are formed at an angle so as to be in facial abutting relationship with an edge surface of the respective rafters 12 and 14.

5 Apparatus for supporting such structural elements in proper relationship and for holding them while they are secured to each other is shown in FIG. 1 and includes a frame consisting of a plurality of upright members 21 which may be maintained at generally erect positions in any desired manner. The upright members 21 may be formed of rectangular stock as shown in FIGS. 2 and 3 and the front face 22 of each post is desirably supported in a substantially vertical plane common with the front 10 face of the other upright members. A first bar 26 adapted to support one rafter in an inverted position is supported near its lower end by a bolt 28 which extends through an intermediate one of the upright members 21. The bar 26 may be hinged about the bolt 28 to change the angular position of the bar 26 in relation to the horizontal. It is for this purpose that the upright member 21a is provided with openings 23 at vertically spaced intervals 15 for receiving a removable bolt or pin 29 which extends through the bar 26 permitting the angular position of the bar 26 to be changed and thereby alter the roof pitch of the truss. A second bar 27 for supporting the other rafter is swingable about a bolt or fixed pivot 31 and the upright member 21b is equipped with vertically spaced holes 25 23 for receiving a removable pin or bolt and the spacing 30 of these holes corresponds to the spacing of the holes in the upright member 21a. Thus the slope of the bar 27 may be altered to correspond to the inclination of the bar 26.

Each upright member 21 carries a flange 33 with its 35 rear face in a common substantially vertical plane with other flanges 33. Each flange 33 is provided with vertically spaced holes. The flanges 33 provide means for supporting a rail 34 along the rear faces of the upright members 21. The rail 34 is supported by removable bolts or 40 pins 36 which extend through the rail 34 and a hole in the respective flanges 33. The position of the bar 34 may be adjusted vertically on the posts 21 but it is desirably maintained in a substantially horizontal position.

An abutment member shown generally at 41 in FIGS. 45 1 and 5 is mounted on each bar 26 and 27 for longitudinal movement with respect thereto. The abutment member 41 carries an upstanding arm 42. These abutment members may be secured in adjusted positions on the bars 26 and 27 by tightening the hand screw 44. In assembling a roof truss the rafter 12 is placed in an inverted manner on the angularly disposed bar 26. The other rafter 14 in its inverted position is arranged on the bar 27. The rafters may be moved downwardly on these bars whereby the angular shaped end surfaces of the rafters are brought in to face to face engagement. The 50 abutment member 41 at the end of the rafter 12 is moved longitudinally on the bar 26 and the arm 42 engages the end surface 43 of the rafter 12 as shown in FIG. 8. The hand screw 44 is then tightened to lock the abutment member 41 on the bar 26. The abutment member 41 on the bar 27 is similarly adjusted and locked. Such means hold the angular end surfaces of the rafters 12 and 14 in abutting relationship.

65 A plurality of hanger stirrups 48 are supported on the rail 34. The hanger stirrups are movable longitudinally on the rail 34 and may be secured in adjusted positions thereon by any suitable means such as the clamp structure shown in FIG. 4. An arm 47 extends laterally from each stirrup as shown in FIG. 4. The bottom chord or 70 ceiling joist 16 is then positioned with one edge on the arms 47 which support the structural element 16 in a substantially correct position with its angular ends 51

(FIG. 8) for face to face engagement with edge surfaces of the respective rafters 12 and 14. While the bottom chord 16 is thus supported web means which may take the form of a king post 17 is arranged in inverted position thereof in proper relationship between the top chord and the bottom chord.

It is important that the dimensions indicated at D in FIG. 10 should be substantially equal. In order to insure proper positioning of the ceiling joist 16 with respect to the rafters two stop members shown generally at 56 are mounted for longitudinal movements on the rail 34. Each stop member may be clamped to the rail 34 by means of a clamping element 57 (FIG. 6). Each stop member 56 carries an abutment plate 58 for engaging the inverted bottom edge of the ceiling joist 16 as shown in FIG. 8. A lip 59 on the plate 58 engages the end of the angular surface 51 on the bottom chord member 16. Such means insures that the bottom chord is in a proper position substantially at right angles to the bisector of the angle formed by the rafters 12 and 14 and with its angular end surfaces in abutting relationship with an edge surface of the associated rafter.

Additional means 61 is carried by the rail 34 and adjustable therealong for maintaining the bottom chord 16 in engagement with the king post 17 or other web means extending between the top and bottom chords. Such means may take the form of a cylinder 62 (FIGS. 7 and 9) adapted to receive air under pressure and move a piston rod 63 to apply vertical force to the joist 16 and position it with respect to the end surface 64 on the king post.

With the structural elements thus held in assembled relationship apertured plates indicated at 66 (FIGS. 9 and 10) may be attached to retain the structural elements to each other and the components of the truss are maintained in proper relationship with each other while the plates 66 are applied. It will be observed that the side faces of the rafters which lie along the front faces of the upright members 21 insures that the rafters are in a common plane. The ceiling joist 16 when gripped by the stop members 56 also promotes attachment of the bottom chord element to the rafters and in a plane common with that of the top chord. The assembled truss may be removed from the apparatus after the means for holding the parts in assembled relationship have been released.

The apparatus may be employed for the manufacture of various types of roof trusses and the arrangement of web means between the top chord and the bottom chord may be varied and formed of more than one element. Various types of devices may be mounted on the rail 34 for supporting and positioning intermediate portions of the bottom chord. While the invention has been described with reference to apparatus of one organization it will be appreciated that changes may be made in the

elements and in the overall assembly. Such modifications and others may be made without departing from the spirit and scope of the invention as set forth in the appended claims.

What I claim and desire to secure by Letters Patent is:

1. Apparatus for making roof trusses comprising, a frame including a plurality of horizontally spaced upright members, a front face on each upright member with all of said front faces in a substantially common vertical plane, a bar mounted at its lower end portion for pivoting about a horizontal axis on an intermediate one of said upright members and inclined upwardly therefrom along the front faces of other of said upright members, one of said upright members near the upper end of said bar having vertically spaced openings therein for receiving removable means supporting the upper end of the bar in different hinged positions, a second bar mounted at its lower end for pivoting movement about a horizontal axis on another intermediate one of said upright members and inclined upwardly therefrom along the front faces of other of said upright members, one of said upright members near the upper end of said second bar having vertically spaced openings therein for receiving removable means supporting the upper end of said second bar in different hinged positions, a substantially horizontal rail extending along rear faces of said upright members, means carried by said upright members for supporting said rail in different vertical positions of the rail, means adjustable along the first bar for engaging a free end of a rafter thereon, means carried by the second bar for engaging a free end of a rafter supported thereon, stop means carried by said rail engaging an end of a bottom chord of a truss where it engages a rafter while it is supported on said bar, and stop means carried by said rail for engaging the other end of a bottom chord of the truss where it engages a rafter while it is supported on the second bar.

2. Apparatus for making roof trusses according to claim 1 wherein the lower end of said first bar is spaced from the lower end of said second bar whereby adjacent ends of the rafters may have free abutting relationship.

3. Apparatus for making roof trusses according to claim 1 including means carried by and movable along said rail for applying vertical force to said bottom chord.
